UNITED STATES PATENT OFFICE.

DAVID F. LAUGHLIN, OF CLYDE, ASSIGNOR OF TWO-THIRDS OF HIS RIGHT TO JOHN MANNING, OF SAME PLACE, AND JOHN H. RANNEY, OF AGENDA, KANSAS, ONE-THIRD TO EACH.

HAY-BURNING ATTACHMENT FOR STOVES.

SPECIFICATION forming part of Letters Patent No. 230,786, dated August 3, 1880.

Application filed January 29, 1880.

To all whom it may concern:

Be it known that I, DAVID F. LAUGHLIN, of Clyde, in the county of Cloud and State of Kansas, have invented certain new and useful 5 Improvements in Hay-Burning Attachments for Stoves; and I do hereby declare that the following is a full, clear, and exact description of the invention, which will enable others skilled in the art to which it appertains to 10 make and use the same, reference being had to the accompanying drawings, which form a part of this specification, and in which—

Figure 1 is a side elevation. Fig. 2 is a longitudinal vertical section. Fig. 3 is a top 15 view, and Fig. 4 is a cross-section through line $x x$, Fig. 3.

Similar letters of reference indicate corresponding parts in all the figures.

This invention has relation to devices for 20 feeding hay, straw, or similar material to stoves for heating, cooking, or other purposes; and it consists in the construction and combination of parts of a device or stove attachment of this class, substantially as hereinafter more 25 fully set forth.

In the drawings, A is a rectangular box of any suitable length, which is supported at its rear end upon feet a , while its front end is inserted through the stove-door into the fire- 30 chamber of the stove or range. As it is important that the mouth of box A should fit closely in the stove-door, angle-irons of suitable width may be employed to form a packing, as it were, and fill out any open space or spaces 35 around the mouth of the box after it has been inserted into the stove. The front part of box A is closed on top; but the greater part of it is open and provided with flaring flanges $b b$, which form a chute or hopper for feeding the 40 straw or hay into the box or magazine.

B is a piston or plunger, which fits into the inside of the box, and has attached to its lower side two parallel arms, $c c$, one in each corner, which are united by a cross-piece, d , 45 to the middle of which is secured the chain C. The forward end of this chain passes over a pulley, e , the periphery of which projects up through a slot in the bottom of the box, while the other end of chain C is passed over a pul-

ley, f , hung in bearings g , projecting from the 50 rear end of the box and up around a windlass, D, which is operated by a crank, D'. This windlass is provided with a pawl, h , and ratchet-wheel i , as shown in Fig. 1 of the drawings.

E is a pyramidal cap or cover, which is inserted into the front end of box A by means of a rod, F, secured at its base, which said rod works in a sleeve, k , and is provided with a handle, F', so that it (the pyramidal cap E) 60 may be adjusted in its relation to the mouth of the box so as to either close this entirely or leave it more or less open by leaving an open space all around it. The handle F' is, by preference, pivoted at the end of rod E, so that it 65 may be locked into any one of a series of slots or notches, l , in the sleeve k , and thus firmly hold cap E in any given position.

A weight, G, is attached to the forward end of chain C, and the piston or plunger B has a 70 notch or slot, m , in its under side, as shown in Fig. 4, to permit it to ride over the chain which passes under it.

From the foregoing description, taken in connection with the drawings, the operation 75 of this apparatus or attachment will readily be understood.

The windlass is turned by its crank D' until the plunger B is drawn all the way back to the rear end of the box, when the straw, hay, 80 or other material to be used as fuel is fed into the box in front of the plunger through the hopper $b b$. The pyramidal cap or shield E is then adjusted so as to permit a certain quantity of the fuel contained in the box to be fed 85 out into the stove, into which the front end of the box A is inserted. By unshipping the pawl h from its ratchet the weight G and chain C will gradually force the plunger B down toward the other (front) end of the box or 90 magazine A, crowding the fuel gradually past the pointed cap E into the stove, where combustion takes place. When the magazine has been exhausted cap E is closed and the plunger is withdrawn by means of the windlass D, 95 when a fresh charge of fuel is put into the box, and so on, from time to time, as occasion requires.

By the use of this magazine fuel is not only economized, but the heat may be regulated with great nicety by simply adjusting the shield E in the manner described. The pyramidal or pointed and flaring shape of this cap or shield prevents choking up of the mouth of the magazine and permits the feeding of the fuel into the stove to proceed with great evenness and regularity. Besides, this attachment is cheap and durable in its construction, and may be applied to any ordinary stove or range without requiring alteration.

I am aware that it is not new to provide a cylinder, attached to a magazine for feeding fuel to a fire-box or stove, with an adjustable stop or shield, with a rack-bar adapted to be adjusted back and forth by a crank-segment engaging with said rack-bar.

Having thus described my invention, I claim

and desire to secure by Letters Patent of the 20 United States—

The combination, with the fuel-feeding box A, with its greater upper portion left open, and provided on each side thereof with an inclined flange, b, and with a follower, B, and 25 its operating mechanism, of the conical or pyramidal shield having a right-angled arm, F, fitting in a tube, k, on the box A, provided with cross-slots l, and having a right-angled arm or handle, F', as set forth.

In testimony that I claim the foregoing as my own I have hereto affixed my signature in presence of two witnesses.

DAVID F. LAUGHLIN.
